UNITED STATES PATENT OFFICE.

CHARLES W. SNYDER, OF LOS ANGELES, CALIFORNIA.

VAPORIZING APPARATUS.

1,386,376.

Specification of Letters Patent.

Patented Aug. 2, 1921.

Application filed March 27, 1917. Serial No. 157,635.

To all whom it may concern:

Be it known that I, CHARLES W. SNYDER, a citizen of the United States, residing at Los Angeles, in the county of Los Angeles, and State of California, have invented a new and useful Vaporizing Apparatus, of which the following is a specification.

An object of this invention is to secure a thorough vaporization of liquid fuels, especially of the heavier hydrocarbons, and at the same time introduce a sufficient quantity of air at a suitable temperature into the vapor produced to prevent the immediate condensation of this vapor. The particular type shown in the drawings is designed especially for converting the liquid fuel used in internal combustion engines into a vapor, and at the same time introducing sufficient air to make a normal mixture for use in these engines. It is evident, however, that the vapor produced in this vaporizer may be used for any suitable purpose and that its use is not confined to internal combustion engines.

As is well known in the art dealing with elastic fluids, if an elastic fluid be introduced into a partial vacuum the vacuum decreases the surface tension, increases the molecular motion and lowers the boiling point of that fluid, thus greatly assisting in the vaporization of the fluid. In this vaporizer I utilize these properties of the vacuum in assisting vaporization and at the same time provide means for introducing into the vapor formed a predetermined amount of air heated to the temperature which is most suitable for the particular fluid which has been vaporized.

The accompanying drawings illustrate the invention:

40 Figure 1 is a plan view showing the vaporizer and an internal combustion engine to which it is connected and with which it functions.

Fig. 2 is an end elevation of Fig. 1.

45 Fig. 3 is an enlarged side elevation, partly in section, showing the side of the vaporizer next to the engine in Fig. 1.

Fig. 4 is a sectional elevation on the line x^4-x^4 , Fig. 5.

50 Fig. 5 is a plan view of Fig. 3, a portion of the hot air pipe being removed.

Fig. 6 is a plan view on the line x^6-x^6 , Fig. 4, showing in section the construction

for admitting fluid to the vaporizer cylinders and a needle valve controlling the admission of this fluid.

Fig. 7 is a section on the line x^6-x^6 , Fig. 4.

Fig. 8 is a fragmental sectional elevation on the line x^8-x^8 , Fig. 6.

In the accompanying drawings my vaporizer is shown as a four cylinder device, but it is evident that the vapor produced by any one cylinder is the same as that produced by any of the other three, therefore the number of cylinders is immaterial, varying with the requirements of the particular purpose for which the vaporizer is used.

Referring to the drawings it will be noticed that the internal combustion engine 1 is provided as is usual with an intake manifold 2 and an exhaust manifold 3, the said intake manifold 2 being in normal connection with my vaporizer.

Referring more particularly to Figs. 3 and 4 it will be seen that the vaporizer is provided with the cylinders 5 containing the pistons 9, said pistons 9 being operated by the crank shaft 11, 12 through the connecting rods 10, the said crank shaft being rotated in the bearings 13 fixed in the ends 75 of the crank case 14.

Each of the vaporizer cylinders 5 are provided with a port 22 through which liquid fuel is admitted to the said cylinders: with one or more air inlet ports 15, and with 85 an exit port 6 through which the mixture of vapor and air is allowed to escape.

The exit port 6 is provided with the valve 7 which is retained on its seat by the light spring 8. The conduit 4 which is a continuation of the intake conduit 2 of the engine 1, is connected through the valve 7 with the interior of the cylinder 5 and receives the mixture of vapor and air from the said cylinders. The conduit 4 is open at one end 90 to the atmosphere so that air can pass into said conduit.

Inasmuch as the vaporization of the heavier fuels requires air at a temperature above the normal atmosphere, I provide the 100 hot air chamber 16 connected with a hot air pipe 17 leading to some convenient source of heat. As shown an extension of this hot air pipe 17 is passed through the exhaust manifold of the engine 1 for the purpose of 105 securing the necessary heated air. In this

hot air pipe 17 I provide a throttle valve 19 for controlling the amount of air admitted to the cylinders 5 of the vaporizer.

In operating an internal combustion engine it is often essential that the vaporizer should furnish a normal mixture to the said engine at a wide range of speeds and for various throttle openings. To meet these requirements I provide a control over the liquid fuel entering the vaporizer, over the air entering the vaporizer cylinders and also over the total volume of mixture entering the cylinders of the engine.

The liquid fuel line 33, leading from any convenient source of liquid fuel supply, may be opened or closed by the valve 34 which is connected to the vaporizer by the union 29 thus allowing the liquid fuel to enter the vaporizer system through the duct 30, the said liquid fuel passing the needle valve 31 and flowing thence right and left to the cylinders of the vaporizers through the pipes 26.

When the vaporizer is a multicylinder device, if the fuel were allowed to flow freely from cylinder to cylinder, the suction stroke of one cylinder would draw the fuel away from all the others. To prevent this action I provide a device of the character shown in Fig. 8, where 23 is the fuel line of the vaporizer, 22 a port through which the liquid fuel enters the cylinder and 24 a ball check valve preventing the return of any fuel from that cylinder.

Any suitable means may be used for controlling the action of the needle valve 31 but I prefer the variable cam plate 35 mounted on the shaft 38, the said cam plate 35 being attached to the quadrant 37, the contour of the surface of its face being controlled by the screws 36. It is understood that the cam plate 35 and the quadrant 37 rock in unison, both being attached to the shaft 38.

The head of the needle valve 31 being always in contact with the face of the cam plate 35, and being retained in this position by the spring 32, it is evident that when the said cam plate is rocked by the lever 38 the needle valve moves toward or away from its seat according to the contour of the face of the cam plate 35, in this way governing the amount of fuel which passes the needle valve.

The usual throttle rod 48 I pivot at 47 to the link 42, then by connecting this link 42 with the cam plate 35 and the throttles 19 and 40 in a manner hereinafter to be described, I am able to control both the liquid fuel and the air passing through the vaporizer, or the total volume of mixture entering the engine.

I provide this link 42 with the opening 43 through which is thrust the bent end of the lever 39 which actuates the cam plate 35.

I provide this link 42 with the slot 45 through which the bent section of the throttle lever 41 may slide, the spring 46 retaining this lever 41 in the left hand end of the slot as shown until the throttle valve 40 becomes completely closed. I also provide this link 42 with the arm 44 which at the instant the throttle valve 40 is closed, comes in contact with the lever 20 of the throttle valve 19 so that further action of this link 42 toward the left closes the throttle valve 19, this latter throttle valve 19 being retained in the open position by the spring 21 until actuated by the arm 44.

When my vaporizer is used to produce fuel for an internal combustion engine, a convenient method of operating it is to provide the sprocket 50 fixed to the end of the crank shaft 12, at the same time attaching a similar sprocket 52 to the cam shaft 53 of the engine 1 and then driving the vaporizer through the chain 51.

As the mixture produced in any one cylinder of this vaporizer is the same as that produced in any other similar cylinder, it is evident that the number of cylinders used is immaterial, a sufficient number being provided to meet the requirements for different uses.

In operation, it is most desirable to secure as great a vacuum as is possible in the cylinders of this vaporizer, therefore the pistons 9 at the beginning of the vacuum stroke are brought as near the cylinder heads as good mechanics will allow.

The instant the piston 9 begins its downward stroke a vacuum commences to form within the cylinder 5, said vacuum constantly increasing until the piston uncovers the air ports 15. As soon as sufficient vacuum has been produced within the cylinder to overcome the inertia of and move the liquid fuel through the port 20 the said liquid fuel begins to flow into the cylinder 5 and continues to flow therein until the vacuum is relieved by the opening of the air ports 15.

During the vacuum stroke of the piston 9 a very small amount of the liquid fuel flows into the cylinder 5. Assuming, for example, that there is one drop of fluid for each two cubic inches of cylinder volume, the amount of air remaining within the cylinder at the beginning of the vacuum stroke is very small and the action of the vacuum tends to expand this small amount of air and the drop of fluid to the two cubic inches of volume. When this vaporization has become fairly complete, air heated to the proper temperature, entering the cylinder 5 through the port 15 tends to maintain and assist the vaporization.

The proper temperature of this heated air entering the cylinders 5 through the ports 15 varies with the different fuels.

The air entering the vaporizer cylinders

5 through the ports 15 may have its temperature raised to the desired point by any suitable means, as, for instance, running the air intake pipe through the exhaust manifold 5 as shown, where the hot air pipe 17 passes through the exhaust manifold 3 of the engine 1.

When the piston 9 returns on its upward stroke, the mixture of vapor and air formed 10 in the cylinders 5 is allowed to escape through the valve 7 into the conduit 4 from which it passes into the engine 1. If the vaporizer does not supply fuel to an engine this conduit 4 will convey the mixture to 15 any place where it is to be used.

As I desire to avoid as much as possible all compression within the cylinders of the vaporizer, I make the valve 7 as light as is 20 consistent and provide it with a spring having just sufficient tension to return the valve to its seat after the cylinders have been emptied.

As the volume of the vaporizer cylinder 25 may be much less than the volume of the cylinder of the engine which it feeds, it is essential that means be provided for varying the amounts of air and liquid fuel entering the vaporizer, and also for varying the auxiliary air entering the engine so that 30 a normal mixture may be secured in the engine at all speeds and with all degrees of throttle openings.

The throttle valve 19 shown as a "butterfly valve" may be of any convenient type, 35 its function being the control of the air entering directly into the cylinders of the vaporizer. The valve 40 also shown as a "butterfly" may be placed in any desired position along the tube 4 of the vaporizer, its 40 function being to control the total volume of air and vapor leaving the vaporizer, that is, when this valve 40 is closed no more charge can enter the engine than can pass through the cylinders of the vaporizer, but 45 when this valve is wide open the charge may equal the full capacity of the conduit 4.

If the throttle rod 48 as shown in Fig. 3, be moved to the right as far as possible the 50 throttles 19 and 40 will be wide open and the needle valve 31 will be at its maximum opening for a correct mixture and the engine will be taking its maximum volume of charge.

In this condition any of the cylinders 5 of 55 the vaporizer is passing into the conduit 4 a mixture over rich in fuel vapor, this over rich mixture being diluted to a normal mixture by the air entering the conduit 4 directly past the throttle valve 40.

60 As the throttle rod 48 is drawn to the left in Fig. 3 of the drawings, it causes the link 42 to gradually close the throttle valve 40 at the same time moving the cam plate 35 attached to the quadrant 37 through the lever 65 39, this motion of the cam forcing the needle

valve 31 toward its seat. This act decreases proportionally both the amount of air passing the throttle valve 40, and the fluid entering the vaporizer past the needle valve 31.

When the link 42 has been brought to the 70 position shown in the drawing the valve 40 is completely closed and all the mixture entering the cylinders of the engine must pass through the cylinders of the vaporizer, and movement of the link 42 from this position 75 on until there is no more mixture entering the cylinders of the engine, the mixture passed from the cylinders of the vaporizer to be a normal mixture.

As the link 42 is advanced farther to the 80 left from the position shown, the throttle valve 40 remains fixed (that is in the closed position) the lever 41 sliding through the slot 45. At the instant the throttle 40 is closed the arm 44 of the link 42 makes a 85 contact with the lever 20, actuating the throttle valve 19, and further leftward movement of the link 42 gradually closes said throttle 19 until it is completely closed. At the same time the motion of the link 42 90 advances the cam 35 thus moving the needle valve 31 toward its seat until the point is reached where neither liquid fuel nor air can enter the vaporizer.

I claim:

1. A vaporizer comprising a vacuum pump, means communicating with the head end of the pump for admitting liquid fuel during the vacuum stroke of said pump, means for admitting air to said pump at or 100 near the end of the vacuum stroke of said pump, means for varying the amount of both liquid fuel and air entering said pump, and means for allowing the mixture to be emitted from said pump at a pressure no 105 greater than atmosphere.

2. A vaporizer comprising a vacuum pump, means for admitting liquid fuel into the head end of said pump, means for admitting air to said pump, a control for varying both the amount of air and of the liquid fuel entering said pump, means for raising the temperature of the air entering said pump above the temperature of the normal atmosphere.

3. In a vaporizer, a vacuum pump comprising a working cylinder and a working piston, a liquid fuel inlet port communicating with the head end of the cylinder for admitting liquid fuel to the said cylinder during the vacuum stroke of said piston, an air inlet port admitting air to the said cylinder at or near the end of the vacuum stroke of said piston, a port allowing the exit of the mixture of vapor and air from the cylinder, 120 means for admitting both the liquid fuel and air to said cylinder in variable amounts as required, means for raising the temperature of the air admitted to said cylinder substantially as described.

115

120

125

130

4. The combination with an engine, of a cylinder, means to supply fuel to the head end of said cylinder, means in conjunction with the engine exhaust pipe to supply hot air to said cylinder, a piston in the cylinder, means operatively connecting the piston to the engine to drive the piston, means connecting the cylinder to the intake of the engine, and means to throttle the hot air supply.
5. The combination with an engine, of a cylinder, means to supply fuel to the head end of said cylinder, a valve to control the fuel supply, means in conjunction with the engine exhaust pipe to supply hot air to said cylinder, a piston in the cylinder, means operatively connecting the engine to the piston to drive said piston, means connecting the cylinder to the intake of the engine, a valve to throttle the hot air supply, and means to operate the air and fuel valves together.
6. The combination with an engine, of a cylinder, means to supply fuel to said cylinder, a valve to control the fuel supply, a mixture passage communicating with the cylinder, a valve to control the flow of air from the atmosphere into said mixture passage, a piston in the cylinder, means operatively connecting the engine to the piston to drive said piston, means connecting the mixture passage to the intake of the engine, and means to operate the air and fuel valves together.
7. The combination with an engine, of a cylinder, means to supply fuel to said cylinder, a mixture passage communicating with the cylinder, a valve to control the flow of air from the atmosphere into said mixture passage, means in conjunction with the engine exhaust pipe to supply hot air to the cylinder, a valve to throttle the hot air supply, a piston in the cylinder, means operatively connecting the engine to the piston to drive said piston, means connecting the mixture passage to the intake of the engine, and means to operate the first named valve and the hot air valve together.
8. The combination with an engine, of a cylinder, means to supply fuel to said cylinder, a valve to control the fuel supply, a mixture passage communicating with the cylinder, a valve to control the flow of air from the atmosphere into the mixture passage, means in conjunction with the engine exhaust pipe to supply hot air to the cylinder, a valve to throttle the hot air supply, a piston in the cylinder, means operatively connecting the engine to the piston to drive said piston, means connecting the mixture passage to the intake of the engine, and
- means to operate all of said valves together.
9. In combination, a cylinder having an air inlet port and an exhaust port, a mixture passage communicating with the exhaust port and adapted to be connected to the intake of an engine, a valve for the exhaust port, a valve to control the flow of atmospheric air into the mixture passage, a piston in the cylinder, and means adapted to operatively connect the piston to an engine shaft.
10. A vaporizer comprising a vacuum pump, means for admitting liquid fuel into the head of said pump during the vacuum stroke of said pump, means for admitting air to said pump at or near the end of the vacuum stroke of said pump, means for varying the amount of said liquid fuel entering said pump, means for varying the amount of air entering said pump, a unit control for varying the amount of air and liquid fuel entering said pump.
11. A vaporizer comprising a vacuum pump, means for admitting liquid fuel into the head end of the pump during the vacuum stroke of said pump, and means for admitting air to said pump at or near the end of the vacuum stroke.
12. A vaporizer comprising a cylinder having a continuously open fuel port, and a working piston in the cylinder, the cylinder having an air port positioned approximately coincident to the end of the vacuum stroke of the piston and adapted to be closed and opened by the piston.
13. A vaporizer comprising a cylinder having means entraining liquid fuel into one end of the cylinder and means entraining air into the other end of the cylinder, and a piston working in the cylinder to create a vacuum for drawing fuel into the cylinder when the vacuum overcomes the inertia of the fuel, the piston opening the air entraining means at or near the end of the vacuum stroke.
14. A vaporizer comprising a vacuum pump, having a cylinder and a working piston, a continuously open liquid fuel port directing fuel into the head end of the cylinder, an air port directing air into the opposite end of the cylinder and uncovered by the piston only at or near the end of its vacuum strokes, and means varying the effective area of the fuel port.

Signed at Los Angeles, California, this 22 day of March, 1917.
